UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKING RETORT OVEN.

Application filed October 13, 1922. Serial No. 594,374.

This invention comprehends improvements of general utility in the coking retort oven art; and also comprehends certain improvements especially applicable to coking 5 retort ovens of the well-known cross-regenerative type exemplified in the patent to H. Koppers, No. 818,035, dated April 17, 1906, and in my prior patent for coking retort oven, No. 1,374,546, dated April 12, 1921. 10 The invention has for objects the provision of a coking retort oven having as the important characteristics: The employment of the cross-over duct principle in a coking retort oven, the vertical flues of which communicate at their upper ends with both interior and exterior horizontal or bus flues, combined with cross-over ducts connecting the individual horizontal flues with the corresponding horizontal flues of an adjacent 15 heating wall; the arrangement of said cross-over ducts in such manner that both the interior cross-over ducts and those located near the side walls of the battery are spaced substantially equidistantly from each other, 20 with the result that equality in distribution of the flow to the various cross-over ducts is attained.

With regard to the novel flue construction, for example, five horizontal flues in 30 each heating wall may be substituted for the usual single horizontal flue which extends from end to end of the heating wall. With a plurality of separate horizontal flues, each flue communicates with a group only of the 35 total number of flues of the heating wall and consequently the dimensions of each flue may be considerably decreased because of the consequent reduction in the volume of flow which must be maintained through the horizontal flue. The above stated reduction in 40 size of the horizontal flues is an important advantage for the reason that it enables a considerable thickening and strengthening of the walls of the oven structure in the region of the horizontal flues. Moreover, the improved flue construction permits an increase 45 in the height of the flame flues with a corresponding increase in the height of the coking chambers so that the latter may be made 50 narrower in width, a development greatly facilitating the coking of high volatile coals,

and yet having adequate provision for taking care of the increased volume of combustion products, without making it necessary to enlarge the horizontal flue dimensions to 55 sizes inconsistent with adequate strength of the wall construction in the region of such flues. The flue construction of the invention is furthermore of great importance in oven batteries fired with extraneously derived gas, 60 such as producer gas, since the employment of such gas results in an increased volume of combustion products and adequate flue spaces must be provided to collect and feed to the downflow operating flues this increased volume of combustion products. By 65 the invention, the flue construction may be adequately accommodated to such increased volume of combustion products, without introducing elements of weakness into the wall 70 structure.

In addition to the objects recited above the invention has for other objects such other improvements or advantages in construction and operation as are found to obtain in the 75 structures and devices hereinafter described or claimed.

In the accompanying drawings, forming a part of this specification, and showing for purposes of exemplification, a preferred 80 form and manner in which the invention may be embodied and practiced, but without limiting the claimed invention to such illustrative instance or instances:

Figure 1 is a crosswise vertical section 85 through a coke oven battery embodying features above specified and equipped with the improvements of the present invention, the view being taken longitudinally through a coking chamber and a pair of regenerators, 90 in planes indicated by the line A—A of Fig. 2;

Figure 2 is a composite vertical sectional elevation taken longitudinally of a coke oven battery, in planes indicated by the lines 95 D—D, E—E of Fig. 1, and F—F of Fig. 3; and

Figure 3 is a composite vertical sectional elevation taken transversely of a coke oven battery, in planes indicated by the lines 100 B—B and C—C of Fig. 2.

In the embodiment illustrated in the draw-

ings, the invention is incorporated in a combination coke oven battery, i. e., a battery having provision for being operated either with producer gas as a fuel, or with coke oven gas burned in an atmosphere of ordinary preheated air, such as is utilized in ordinary coke ovens, or with coke oven gas burned in an atmosphere containing both air and a neutral gaseous diluent which is introduced into the flame flues separately from the air. A combination coke oven battery having these features is described and claimed in my prior patent dated May 16, 1922, for a coking retort oven, No. 1,416,332. 10
15 For convenience, the present description will be confined to the present illustrated embodiment of the invention in such a combination oven battery; the novel features and improvements made by the invention, are 20 susceptible of other applications, such, for example, as ordinary so-called "coke ovens" employing coke oven gas as a fuel, or ordinary so-called "gas ovens" employing producer gas as a fuel; hence, the scope 25 of the invention is not confined to the specific use and specific embodiment herein described as an illustrative example.

Referring to the drawings, there are 30 illustrated views of a coke oven battery or plant of the by-product type, having features above specified; said oven battery embodies in its construction a plurality of crosswise elongated heating walls 11, 11, and a plurality of intermediate crosswise 35 elongated vertical coking chambers 12, 12. The heating walls 11 form the side walls of the respective coking chambers 12, as shown more particularly in Fig. 2, and, in the present instance, are directly supported 40 by the heavy supporting or pillar walls 13, 13 which extend crosswise of the battery and are located, as shown in Fig. 2, beneath the respective heating walls 11, 11. These 45 pillar walls, together with other walls, hereinafter described, collectively form the main support for the entire super-structure of the oven battery and are themselves supported upon a flat mat or platform which constitutes the sub-foundation on which 50 the entire battery rests. The coal to be coked is charged into the several coking chambers or ovens through charging holes 14 located in the top 15 of the oven battery and positioned directly above the oven 55 or chambers 12, as shown in Figs. 1, and 2. These charging holes 14 are equipped with the usual removable covers, which are removed during charging of the individual ovens or coking chambers and are placed 60 in position to close the tops of such coking chambers during the entire coking or distilling operation. The gases of distillation pass from the tops of the several coking chambers 12 through gas outlets 16 and 65 thence through ascension pipes (not shown)

into the usual gas collecting main which carries the distillation products to the by-product recovery apparatus.

Heat for coking the charges of coal in the several ovens or chambers 12 is derived from 70 the heating walls 11, which, as above mentioned, extend crosswise of the battery at the sides of the coking chambers. Referring now more particularly to Figs. 2 and 3, each heating wall 11 is constituted of a 75 plurality of flame or combustion flues 17. The flame flues of each heating wall are, in accordance with the invention, operatively disposed into a single group, that is to say 80 all of the flues of each heating wall operate concurrently as upflow or downflow flues, as will be hereinafter more fully explained. When the flame flues on one side of a coking chamber are burning, that is to say, operating for upflow, the flame flues 85 on the opposite side of the same coking chamber are operating for downflow to permit exhaust of the waste gases. Consequently heating is maintained continuously from end to end on one side of a charge of 90 coking coal in each coking chamber, the heat being applied to the full length of one side of such charge during an entire period and, then, after reversal, being applied to the 95 full length of the opposite side of the charge, until a subsequent reversal is effected.

The crosswise regenerators 18 of the retort oven or battery are located in planes beneath the planes of the aforesaid heating walls 11 and coking chambers 12, and, in the present instance, extend in parallelism 100 between the pillar walls 13, and the other heavy supporting walls, hereinafter described. Located in the middle lengthwise vertical plane of the coke oven battery, is 105 a vertical partition 19, as shown in Fig. 1, which partition extends all the way up from the mat of the battery to the bottom of the overlying coking chamber and from one to the other of the pillar walls 13, and the other 110 walls which are between the pillar walls. The regenerators, which are respectively located on opposite sides of the battery extend inwardly to said partition 19 and are separated thereby as clearly shown in Fig. 1. 115 This arrangement permits control from opposite sides of the battery of the flow through the regenerators, thereby assisting the novel flue arrangement in promoting uniformity of distribution. Each regenerator 18 is a chamber containing open brick work, commonly called checker work, and indicated at 20, with a distributing sole channel 21 underneath such checker work, 120 the channels forming the soles of such chambers and opening up into the checker work. In accordance with the invention, a heavy vertical gas-tight supporting wall 22 extends directly beneath the coke chamber in parallelism between each two adjacent pillar 125 130

- walls 13 and such supporting walls 22 provide two regenerators G and H located respectively on the opposite sides of such walls 22 and between adjacent pillar walls 13. 5 The several walls 22 also have the function with the pillar walls 13 of supporting the weight of the battery super-structure.
- This supporting wall construction provides two series of crosswise-extending 10 parallel gas-tight load-carrying walls located below the coking chambers and intermediate heating walls, the supporting walls of one series 13 being directly beneath the heating walls and the supporting walls of 15 the other series 22 being directly beneath the coking chambers. The walls 22 which are beneath the coking chambers are constructed and function not as mere partitions commonly employed, but as true load-carrying 20 gas-tight walls, permitting relatively different pressures to be maintained in the checker work chambers on the opposite sides of such walls, or the flow of different media in the checker work chambers separated by these 25 walls, without leakages from one checker work chamber into another and without danger of mixing gases in the checker work chambers which must be kept separate in this region of the battery.
- 30 The regenerators G and H are heated, in alternation, by the hot combustion products that draw off from the flame or combustion flues hereinbefore mentioned and then impart such heat to the medium that they feed 35 into these flame flues; in the present instance, the flow through the regenerators G, H between each two adjacent pillar walls is maintained concurrently in opposite directions, for example, when the flow is passing 40 up through a regenerator G, downflow is being maintained concurrently through the other regenerator H. Each regenerator is provided with a series of ducts 23 all of 45 which lead respectively to individual flame flues 17 of the same heating wall, whereas the ducts 23 of the other regenerator between the same pillar walls 13 lead respectively to individual flame flues 17 of the next adjacent heating wall, as clearly shown in Fig. 50 2. With this construction each flame flue 17 communicates by a pair of ducts 23 with adjacent separate regenerators H, G, and the flow through the regenerators H, G which are respectively located on opposite sides of 55 a pillar wall 13, is maintained concurrently in the same direction, that is to say both said regenerators are either operating for inflow or for outflow.
- In the present embodiment of the invention, the entire series of flame flues 17 of 60 each heating wall 11 is either burning or operating for downflow to convey waste products to the regenerators beneath and consequently the regenerators alined on opposite 65 sides of the central longitudinal partition 19 operate concurrently for flow in the same direction and in the same manner. The reversal in flow through the flame flues 17 on opposite sides of a coking chamber, and their communicably connected regenerators 70 may thus be said to take place longitudinally of the oven battery, instead of transversely thereof, as has heretofore been a common practice in this art. The reversal of the oven is effected at the end of an operating period determined by practice, and by means of any preferred type of reversing mechanism. The function of such reversal is as follows: The regenerators that prior to the reversal operated as inflow regenerators 75 become outflow regenerators, and the outflow operating regenerators become inflow operating regenerators; the upburning series of flue switches function with the downburning series of flues of the next adjacent heating wall, and the supply of gas is turned off from the previously upburning flues and turned on into the mains of the previously downburning flues.
- Each flame flue 17 of each heating wall has 80 at its top a port or opening 24 for draft and the passage of combustion products or waste gas from the flame within the flue. These ports 24 open up into horizontal or bus flues 25 formed in the heating walls and 85 connecting all of the vertical flues that communicate with such horizontal flues 25 by means of the ports 24. According to the invention, there are in each heating wall a plurality of, in the present instance, five 90 of such horizontal flues 25 positioned end to end with respect to each other and respectively constituted of the three interior flues 25^a and the two side flues 25^b, the several flues being of substantially equal length. 95 By reason of the fact that there is a plurality of such horizontal flues 25, these flues 25 are not required to be of so great capacity as that necessary in present practice and consequently the cross-sectional area of each 100 horizontal flue 25 may be materially reduced proportionately with the length of such flue, with the result that the thickness and strength of the heating walls are substantially increased in the region of the horizontal flues. Moreover, because of the fact that each horizontal flue 25 communicates with a substantially reduced number of vertical flues, in the present instance only about 105 one fifth of the flues of a heating wall, uniformity in distribution of the flow through the vertical flues and the communicating regenerators is greatly promoted.
- As shown, the several horizontal flues 25 of each heating wall are communicably connected respectively by means of passageways or cross-over ducts 26 with the corresponding horizontal flues of one of the next adjacent heating walls. These cross-over ducts 110 extend over the top of the coking chamber be- 115
- 120
- 125
- 130

tween the communicably connected horizontal flues of the pair of adjacent heating walls, and the interior or intermediate cross-over ducts 26^a are spaced at mutually equal distances from each other. The two side or outer cross-over ducts 26^b are also respectively spaced at mutually equal distances from the adjacent interior cross-over ducts 26^a and the spacing between each pair of the entire series of ducts of the heating wall is substantially equal. The words "outer" and "intermediate" are terms employed for convenience, the term "outer" to indicate the cross-over flues that serve the group of flame-flues nearest the outside or exposed faces, and the term "intermediate" to indicate the cross-over flues that serve the groups of flame-flues nearer the middle or interior and less exposed region of the battery. With this construction the flow from individual groups containing respectively substantially the same number of vertical flues passes into and through horizontal flues all of substantially equal length and is by the cross-over ducts, which are disposed at substantially equal distances apart, conveyed in equally distributed streams to the corresponding horizontal flues and their communicably connected groups of flame flues of the next adjacent heating wall. Moreover, the individual horizontal flues with their individual cross-over duct connections permit separate regulation in the interior of the battery structure to preserve the desired equality in flow. The multiplicity of cross-over ducts serves to give the equality of distribution to and from the groups of vertical flues even if each of the horizontal flues is not separated from the other horizontal flues in the same heating wall therewith by partitions between their ends or if the partitions are not tight. The entire flow from a heating wall, within the flues of which combustion is being maintained passes through and downwardly through all of the flues of the next adjacent heating wall and each reversal operation is accompanied by a reversal in direction inflow of all of the flues of each heating wall.

The draft through the ports 24 may be regulated by means of the usual movable dampers or sliding bricks 27, positioned in the ordinary way in the bottoms of the horizontal flues 25 and adapted to be reached by access flues 28 which extend from the top of the horizontal flues 25 in each heating wall to the top 15 of the battery, there being an access flue positioned over each flame or combustion flue of each heating wall.

Extending crosswise of the battery in each pillar wall 13 and located beneath the heating wall 11 thereabove, is a pair of gas-supply channels 29 and 30. These channels 29 and 30 are for the purpose of supplying coke oven gas to the several flame flues on each side of the central line L, and to accomplish

this end, the channel 29 communicates with the individual flues 17 on the near side of said line L by means of ducts 31 that lead from such channel 29 individually into the bottoms of individual flues; and the channel 30 which supplies the several flues that are located on the far side of the aforementioned dividing line L communicates therewith by means of similarly connecting ducts. Within the several ducts are disposed the usual nozzles 32. The supply of coke oven gas to the respective channels 29 and 30 is derived from coke oven gas mains of the usual type and respectively located on the opposite sides of the battery and extending longitudinally therealong. Suitable means is provided for admitting or cutting off the supply of gas with respect to each pair of channels 29 and 30, it being understood that the gas supply is either concurrently maintained or concurrently shut off from both channels of each pair. For operating the battery alternatively with the use of a special generator gas, such as producer gas as a fuel, the several regenerators H may be optionally connected with a producer gas main, by mechanism such as is disclosed in my before-mentioned Patent No. 1,416,322, so that the producer gas may be directed into such of the regenerators H as are operating for inflow and conveyed through these regenerators into burning flame flues 17.

The operation of the retort oven or battery, when using a special generator gas, such as ordinary producer gas is as follows: The supply of coke oven gas to the coke oven gas main and to all of the coke oven gas channels 29, 30, is cut off. A supply of producer gas is permitted to flow into the alternate regenerators H, such as are operating for inflow and passing through said regenerators is preheated before being delivered into the burning flame flues. During the inflow of producer gas through such alternate regenerators H waste gas from the downburning flues is flowing out through the other regenerators G as well as through the other regenerators H that are intermediate such alternate regenerators H, as indicated by arrows and letters on Fig. 2. In the intermediate regenerators G, inflow of air is maintained and passing upwardly through such regenerators finally enters the burning flame flues to support the combustion of the producer gas that is delivered thereto by the alternate regenerators H. On reversal of the flow, the inflow operating regenerators become outflow regenerators and concurrently the outflow operating regenerators become inflow regenerators.

In operating the battery with coke oven gas in the ordinary manner, the supply of producer gas to alternate regenerators H is shut off and air is permitted to flow into such regenerators in place of the producer gas,

During coke oven gas operation, a supply of coke oven gas is maintained in the channels 29 and 30 which feed the upburning flues. The reversing mechanism is operated at each 5 reversal to place all of the inflow operating regenerators in communication with the outer air and concurrently all of the outflow operating regenerators in communication with the exhaust. A further mode of operation 10 is with coke oven gas as a fuel, combined with a supply of neutral gaseous diluent to the upburning flues. In so operating the battery, the supply of producer gas is turned off and the supply of coke oven gas is turned 15 on. Instead however of permitting air to flow into alternate regenerators of the series H that serve for producer gas, during the latter operation, waste gas is permitted to flow into such regenerators and be delivered 20 thereby to the upburning flame flues. The admission into each of the upburning flues of a supply of the neutral gaseous diluent, such as waste gas, is effective to lengthen 25 greatly the flames within such flues and to prevent the localization of the hottest flame temperature in the extreme lower portions 30 of the flues.

The invention as hereinabove set forth is embodied in a particular form of construction but may be variously embodied within 35 the scope of the claims hereinafter made.

The invention described or claimed in this application is a continuation in part of my original application for Letters Patent of 35 the United States for coking retort oven, Serial No. 490,086, Patent No. 1,524,120 filed August 5, 1921.

I claim:

1. In a coking retort oven, in combination: 40 heating walls forming a plurality of coking chambers; said heating walls being constituted of vertical combustion flues; outer and intermediate horizontal flues in each heating wall and respectively communicably connected with outer and intermediate groups of the combustion flues of their respective heating walls; the horizontal flues being each of substantially equal length and being also communicably connected individually by duct means extending over the top of the coking chamber with the corresponding horizontal flues of an adjacent heating wall; and regenerators communicably connected with said heating walls; substantially 55 as specified.

2. In a coking retort oven, in combination: 60 heating walls forming a plurality of coking chambers; said heating walls being constituted of vertical combustion flues; outer and intermediate horizontal flues in each heating wall and respectively communicably connected with outer and intermediate groups of the combustion flues of their respective heating walls; the horizontal flues 65 being also communicably connected individ-

ually by duct means extending over the top of the coking chamber with the corresponding flues of an adjacent heating wall; and regenerators communicably connected with said heating walls; substantially as specified. 70

3. In a coking retort oven, in combination: heating walls forming a plurality of coking chambers; said heating walls being constituted of vertical combustion flues; outer and intermediate horizontal flues in each heating 75 wall and respectively communicably connected with outer and intermediate groups of the combustion flues of their respective heating walls; the horizontal flues being also communicably connected with the corresponding flues of an adjacent heating wall; and regenerators communicably connected with said heating walls; substantially as 80 specified.

4. A coking retort oven with coking chambers having vertically flued heating walls interconnected in pairs by means of cross-over passages extending over intervening coking chambers and which are adapted to allow draft reversal therethrough, characterized by the cross-over passages consisting of outer and intermediate overhead passages joining horizontal bus flues in the interconnected heating walls and by more than two horizontal flues of substantially equal 95 length in each heating wall.

5. A coking retort oven with coking chambers having vertically flued heating walls interconnected in pairs by means of cross-over passages extending over intervening 100 coking chambers and which are adapted to allow draft reversal therethrough, characterized by cross-over passages consisting of outer and intermediate overhead passages joining horizontal bus flues in the interconnected heating walls and by the overhead ducts or passages being substantially equidistant from each other.

6. In a coking retort oven, in combination: a series of horizontal coking chambers; 110 heating walls intermediate the coking chambers and each having a plurality of vertical flame flues therein; a horizontal flow duct means in each of the heating walls on opposite sides of one of the coking chambers and communicably connected with the vertical flame flues therein; a multiplicity of at least four crossover conduits crossing over the coking chamber and communicably connecting the horizontal flow duct means in the 115 heating wall on one side of the coking chamber with the horizontal flow duct means in the heating wall on the opposite side of the coking chamber, each of said horizontal flow duct means having a portion between each 120 two of said crossover conduits, said crossover conduits being spaced from each other and from the ends of the heating walls so that each of said crossover conduits is communicably connected at each end thereof 130

with vertical flues on opposite sides thereof along the heating walls by means of the said horizontal flow duct means; said crossover conduits being also distributed along the

vertical flues that communicate with the portion of the horizontal flow duct means between said each two of said crossover conduits.

10

5 horizontal length of the coking chamber so that each of them accommodates gas flow to and from substantially only a part of the

In testimony whereof I have hereunto set my hand.

JOSEPH BECKER.
